STOCK QUOTATION MULTIPLE PROJECTING MACHINE

August D. Eitzen, Rockville Center, N. Y., assignor to News Projection Corporation, New York, N. Y., a corporation of New York

Application September 4, 1929, Serial No. 390,371
Renewed May 8, 1933

25 Claims. (Cl. 88—24)

My present invention relates generally to stock ticker apparatus, and has particular reference to an improved type of stock quotation projecting machine.

- 5 It is frequently desirable to project the markings on a tape emanating from a stock ticker toward two or more distinct and different observation areas. For example, it may in certain cases be desirable to display these markings into 10 two rooms reserved respectively for men and women, or it may be desirable to project the markings toward a main observation area and also toward or into a private office or the like. 15 It is an object of my present invention to provide a projection machine which permits of the foregoing dual display, and it is a particular object to provide an apparatus which embodies a maximum of simplicity and a minimum of expense. 20 Inasmuch as stock tickers and projecting devices are comparatively expensive in certain localities, whether bought or rented, it is a particular object of my present invention to provide for a multiple display of the tape markings without 25 recourse to any more than a single stock ticker and a single projecting device of normal character.

It is a particular feature of my invention, pursuant to the foregoing general objects, to provide 30 a projecting device which is so constructed that the single source of light customarily embodied therein may be employed to the greatest advantage in creating two distinct and differently directable beams of light. More particularly, I 35 provide a pair of outlet apertures for the light, and I also provide suitable means for drawing the tape successively across these two apertures.

A further feature of my invention lies in arranging the two apertures above referred to in 40 mutual parallelism and in side by side relationship, and to provide tape-pulling means and guiding means for directing the tape first across one of the apertures in one direction and then 45 across the other aperture in the opposite direction.

For the attainment of the foregoing objects and such other objects as may hereinafter appear or be pointed out, I have illustrated several forms of my invention in the accompanying drawings, 50 wherein—

Figure 1 is an elevational view, largely diagrammatic, of a machine embodying the features of my present invention;

Figure 2 is a view taken from the left of Figure 1, with the screens omitted for the sake of clearness and illustrating also a possible arrangement of a tape-pulling mechanism;

Figure 3 is a plan view of a portion of the projecting device, showing the manner in which the tape is guided across the apertures referred to;

Figure 4 is a view taken substantially in the same direction as Figure 1, showing one practical installation of the present character;

Figure 5 is a perspective view of an important element of the tape-guiding means; and

Figure 6 is a diagrammatic representation similar to Figure 1 and illustrating a modification.

Referring to Figures 1 and 2, I will point out that I have shown a stock ticker 10 of usual construction adapted to discharge a marked tape 11, the latter being guided into a projecting device 12. In accordance with my present invention, the tape 11 leaves the projecting device at the same side at which it enters, and I have illustratively shown the manner in which this tape may be guided downwardly around rollers 13 and 14 toward a suitable tape-pulling and rewinding mechanism. The latter may embody a source of power such as the motor 15 which drives a worm 16, the latter meshing with and rotating a worm wheel 17, and thereby driving the shaft 18. The tape 11 may be made to pass downwardly beneath the guide roller 19, thence upwardly around the shaft 18, then downwardly beneath the second 25 guide roller 20, and where the tape is to be rewound, it may then pass onto a mandrel 21. The latter may be rotated or driven from the shaft 18 by means of the belt 22. A pressure roller 23 is advantageously positioned so as to bear down upon the tape as it passes over the shaft 18. 30

In Figure 1 I have shown the possible arrangement within the projecting device 12 of a single source of light 24 adapted to project a beam of light through a pair of condensing lenses 25 and 26, this beam being thereupon reflected into an upward direction by means of a mirror 27. Above the mirror 27, the usual outlet aperture for the light beam is arranged, and in accordance with my present invention I provide a particular type 40 of outlet aperture or apertures hereinafter more fully to be described.

In Figure 1 I have also shown the arrangement of two screens 28 and 29 facing in opposite directions and being adapted thereby to serve different 45 observation areas.

Immediately above the center of the beam directed upwardly by the mirror 27 I arrange two outlet apertures 30 and 31, most clearly shown in Figure 3. These apertures are preferably arranged in mutual parallelism and alongside of each other, and these two apertures are in effect a single aperture of a width substantially twice that of the tape. In accordance with my invention, the tape 11 is drawn through the projecting device in such a manner that it will successively pass across the two apertures 30 and 31. Referring to Figure 3, it will be seen that the tape 11, upon entering the projecting device, passes toward the right across the aperture 30. At the 60

opposite end of the projecting device, the tape-reversing guide 32 directs the tape downwardly and rearwardly, thence upwardly again and toward the left. The guide 32 is so positioned and shaped that the tape will be accurately guided over the aperture 31 in its return passage through the projecting device. The tape then leaves the projecting device by passing over the guide roller or the like 33.

10 In Figure 5 I have illustrated a simple construction of the guide device 32. It is to be noted that it is substantially V-shaped and embodies a pair of angularly disposed rounded guiding surfaces 34 and 35. These surfaces are at substantially 15 90° to each other and are respectively at substantially 45° to the axes of the apertures 30 and 31.

Referring again to Figure 1, it will be seen that the provision of two apertures in the foregoing 20 manner results in the creation of two light beams 40 and 41 passing upwardly from the apertures 30 and 31 respectively. For projecting the light beam 40 onto the rear face of the screen 28, I provide an objective lens 42 mounted upon a suitable standard 43, and above this lens and behind 25 the screen 28 I provide the two angularly disposed reflecting surfaces or mirrors 44 and 45.

For projecting the beam 41 onto the rear face of the screen 29, I provide first a mirror 46 which 30 deflects the beam 41 rearwardly through an objective lens 47, after which a set of mirrors 48, 49, and 50 serve to direct the beam onto the screen 29.

In Figure 4 I have shown a practical embodiment of my invention. 51 represents a wall or partition separating a main room at the left from a private office at the right. For example, 52 may represent the desk in the private office. A suitable pedestal or stand 53 supports the ticker 40 54 and the projecting device 55, and apparatus of the character hereinbefore described in greater detail projects the markings not only upon the screen 56 mounted in the wall 51 and facing the room at the right of the wall, but also onto the 45 screen 57 facing toward the left and displaying the markings toward the larger observation area.

While it is true that the markings projected upon the screen 56 (and upon the screen 29 of Figure 1) will be those which have already been 50 projected upon the screen 57 (or upon the screen 28), this slight delay is not sufficient to outweigh the great advantages achieved by non-duplication of expensive apparatus. As a matter of fact, the amount by which the second screen displays are 55 behind the displays of the first screen is extremely slight, as will be appreciated upon reference to Figure 3, wherein it is clear that the tape is guided in the most direct manner across the two apertures successively.

60 In Figure 6 I have illustrated a modification wherein the screens are differently positioned. Thus, I have shown a screen 58 positioned at the lower left and facing toward the right and deriving its beam of light 59 from the beam 60 emanating from the aperture 31. The beam 60 is directed onto the screen 58 through an objective lens 61 and by means of a pair of mirrors 62 and 63. Similarly, the beam 64 emanating 65 from the aperture 30 is directed upwardly 70 through a lens 65 onto a mirror 66 which projects the beam toward the right onto a screen 67. This modification illustrates the fact that from certain aspects my invention is independent of the particular arrangement of the two or more screens that might be employed.

I do not wish to limit myself to the provision of two apertures, nor to the particular parallel arrangement herein illustrated, although such arrangement has proven to be highly satisfactory.

Furthermore, it will be obvious that changes 5 in the details herein described and illustrated for the purpose of explaining the nature of my invention may be made by those skilled in the art without departing from the spirit and scope of the invention as expressed in the appended 10 claims. It is therefore intended that these details be interpreted as illustrative, and not in a limiting sense.

Having thus described my invention and illustrated its use, what I claim as new and desire 15 to secure by Letters Patent is—

1. In a stock ticker projection machine, a ticker adapted to discharge marked tape, a projecting device including a source of light and a pair of outlet apertures therefor, a pair of screens, 20 means for drawing the tape successively across said apertures, and means for projecting the light beams from said apertures onto said screens respectively; said last-named means comprising a single objective lens and a set of mirrors for each 25 light beam.

2. In a stock ticker projection machine, a ticker adapted to discharge marked tape, a projecting device including a source of light and a pair of outlet apertures therefor, a pair of 30 screens facing in opposite directions, means for drawing the tape successively across said apertures, and means for projecting the light beams from said apertures onto the rear faces of said screens respectively, said last named means comprising a single objective lens and a set of mirrors for each light beam.

3. In a stock ticker projection machine, a ticker adapted to discharge marked tape, a projecting device including a source of light and a pair of outlet apertures therefor, said apertures being arranged in parallelism side by side, means for drawing the tape through said device and guiding it successively across said apertures, a pair of screens, and means including a set of 45 mirrors for the light beam from each aperture for projecting such light beams onto said screens.

4. In a stock ticker projection machine, a ticker adapted to discharge marked tape, a projecting device including a source of light and a pair of outlet apertures therefor, said apertures being arranged in parallelism side by side, means for drawing the tape through said device and guiding it across one of said apertures in one direction and then across the other aperture in 5 the opposite direction, a screen for each light aperture, and means including a set of mirrors for the light beam of each aperture for projecting such light beams onto said screens.

5. In a stock ticker projection machine, a ticker adapted to discharge marked tape, a projecting device including a common source of light and a pair of outlet apertures therefor, said apertures being arranged in parallelism side by side, the discharge end of the first aperture adjoining the entrance end of the second aperture, tape-pulling means for drawing the tape through said device, and means disposed adjacent to said adjoining ends of the apertures for guiding the tape so that it will pass successively across said apertures and cause the same subject matter successively to appear first at the first aperture and then at the second aperture with a minimum loss of quotations between successive light apertures.

6. In a stock ticker projection machine, a ticker adapted to discharge marked tape, a projecting device including a source of light and a pair of outlet apertures therefor, said apertures being arranged in parallelism side by side, the discharge end of the first aperture adjoining the entrance end of the second aperture, tape-pulling means for drawing the tape through said device, and means disposed adjacent to said adjoining ends of the apertures for guiding the tape so that it will pass successively across said apertures and cause the same subject matter successively to appear first at the first aperture and then at the second aperture with a minimum loss of quotations between successive light apertures, said last-named means including a reversing guide at one end of the projecting device.
7. In a stock ticker projection machine, a ticker adapted to discharge marked tape, a projecting device including a source of light and a pair of outlet apertures therefor, said apertures being arranged in parallelism side by side, tape-pulling means for drawing the tape through said device, and means for guiding the tape so that it will pass successively across said apertures, said last-named means including a V-shaped tape-reversing guide at one end of said apertures.
8. In a stock ticker projection machine, a ticker adapted to discharge marked tape, a projecting device including a source of light and a pair of outlet apertures therefor, said apertures being arranged in parallelism side by side, tape-pulling means for drawing the tape through said device, and means for guiding the tape so that it will pass successively across said apertures, said last-named means including a pair of angularly disposed rounded guide surfaces at one end of said apertures and aligned with the latter respectively.
9. In a stock ticker projection machine, a ticker adapted to discharge marked tape, a projecting device including a source of light and a pair of outlet apertures therefor, said apertures being arranged in parallelism side by side, tape-pulling means for drawing the tape through said device, and means for guiding the tape so that it will pass successively across said apertures, said last-named means including a rounded guide surface at one end of one of said apertures and at substantially 45° to the axis of the latter, and a second similar rounded guide surface at the corresponding end of the other aperture and at substantially 90° to the first-named guide surface.
10. In a stock ticker projection machine, a ticker adapted to discharge marked tape, a projecting device including a common source of light and a pair of outlet apertures therefor, said apertures being arranged in parallelism side by side, the discharge end of the first aperture adjoining the entrance end of the second aperture, tape-pulling means for drawing the tape through said device, means disposed adjacent to said adjoining ends of the apertures for guiding the tape during its passage through said device so that it will pass successively over said apertures and cause the same subject matter successively to appear first at the first aperture and then at the second aperture with a minimum loss of quotations between successive light apertures, and a pair of screens in different inspection areas adapted to receive the light beams emanating from said apertures respectively so that the same projected subject matter may be inspected from two different inspection areas.
11. In a stock ticker projection machine, a ticker adapted to discharge marked tape, a projecting device including a common source of light and an outlet aperture therefor of a width substantially twice that of the tape, means for drawing the tape across one longitudinal half of said aperture in one direction and then across the other longitudinal half in the other direction, so that the same subject matter will first appear at one half and then at the other half of said aperture with a minimum loss of quotations between successive halves, and a pair of screens disposed in different inspection areas arranged to receive the light beams emanating from said longitudinal halves respectively, whereby two independent displays of the same tape markings are provided for in two different inspection areas.
12. In a stock ticker projection machine, a ticker adapted to discharge marked tape, a projecting device including a common source of light and an outlet aperture therefor of a width substantially twice that of the tape, means for drawing the tape across one longitudinal half of said aperture in one direction and then across the other longitudinal half in the other direction, so that the same subject matter will first appear at one half and then at the other half of said aperture with a minimum loss of quotations between successive halves, a pair of screens facing in opposite directions, and optical means associated with respective screens for projecting thereon the light beams emanating from said longitudinal halves respectively, whereby the same markings on said tape are displayable, by a single light source, toward two distinct observation areas.
13. In a stock ticker projection machine, a ticker adapted to discharge marked tape, a projecting device including a source of light and a pair of outlet apertures therefor, a pair of screens, means for drawing the tape successively across said apertures, and means for projecting the light beams from said apertures onto said screens respectively; said last-named means comprising a single objective lens and reflecting means for each light beam.
14. In a stock ticker projection machine, a ticker adapted to discharge marked tape, a projecting device including a source of light and a pair of outlet apertures therefor, a pair of screens facing into different inspection areas, means for drawing the tape successively across said apertures, and means for projecting the light beams from said apertures onto said screens respectively; said last-named means comprising a single objective lens and reflecting means in the path of each light beam and serving to direct said beam upon one of said screens.
15. In a stock ticker projection machine, a ticker adapted to discharge marked tape, a projecting device including a source of light and a pair of outlet apertures therefor, a plurality of screens facing into different inspection areas, means for drawing the tape successively across said apertures, and means for projecting the light beams from said apertures onto said screens; said last-named means comprising a single objective lens and reflecting means for each light beam.
16. Projecting apparatus of the character described comprising a housing having closely adjacent parallel light apertures, a common source of light for throwing light through the apertures, means for successively guiding and directing a

continuous printed tape over the apertures, an objective lens group for each aperture, one arranged to receive a light beam directly from its aperture, and a mirror angularly arranged between the second aperture and its objective to intercept the beam from the aperture and direct it to its objective.

17. Projecting apparatus of the character described comprising a housing having adjacent parallel light apertures, a common source of light for throwing light through the apertures, means for successively guiding and directing a continuous printed tape over the apertures, an objective lens group for each aperture, one arranged to receive a light beam directly from its aperture, a mirror angularly arranged between the second aperture and its objective to intercept the beam from the aperture and divert it to the other objective, a screen and mirrors arranged to direct the beam from the first objective to the screen, another screen, and mirrors arranged to direct the beam from the second objective to said screen.

18. Projecting apparatus of the character described comprising a housing having adjacent parallel light apertures, a common source of light, means for successively guiding and directing portions of a successive continuous printed tape over the apertures, means for directing a converging light beam from said common source of light at said adjacent light apertures to form two subordinate light beams after emerging from the two tapes, an independent screen for the images produced by the portion of tape at each light aperture, reflecting means arranged to direct a subordinate beam emerging from one portion of the tape to one of said screens, and another reflecting means arranged to direct the subordinate beam emerging from the other portion of the tape to the other of said screens.

19. Projecting apparatus of the character described comprising a single source of light and a plurality of light apertures therefor, a pair of rear projection screens facing in inspection areas spaced from one another, means for successively drawing marked tape across said light apertures to produce image impressed light beams, and means for projecting such image impressed light beams onto the rear faces of said screens, said latter means including mirrors and an objective lens unit for each light aperture disposed within the area located behind said screens and between said inspection areas.

20. In a stock ticker projection machine, a ticker adapted to discharge marked tape, a projecting device including a source of light and a pair of horizontally extending outlet apertures therefor, a pair of substantially vertically extending screens, means for drawing the tape successively across said apertures through horizontally extending planes, and means for projecting the light beams from said apertures onto said screens respectively; said last-named means comprising a single objective lens and reflecting means for each light beam.

21. In a stock ticker projection machine, a ticker adapted to discharge marked tape, a projecting device including a source of light and a pair of outlet apertures therefor, a pair of rear projection screens, means for drawing the tape successively across said apertures, and means for

projecting the light beams from said apertures onto the rear faces of said screens respectively; said last-named means comprising a single objective lens and reflecting means for each light beam.

22. The combination with a tape having reading matter formed thereon readable longitudinally of the tape, of a projecting apparatus comprising a source of light, two light apertures, means for successively drawing said tape across said light apertures in opposite directions to form two image impressed light beams, two screens, and means for projecting said image impressed light beams onto said screens respectively, said last-named means including a single objective lens unit for rotating the image one hundred and eighty degrees from end to end and reflecting means for each light beam whereby the images on the screens will move in a direction opposite to that of the tape portion being projected.

23. The combination with a tape having reading matter formed thereon readable longitudinally of the tape, of a projecting apparatus comprising a source of light, two light apertures, means for successively drawing said tape across said light apertures in opposite directions with the readable matter facing upwardly to form two image impressed light beams, two screens, and means for projecting said image impressed light beams onto said screens respectively, said last named means including a single objective lens unit for rotating the image one hundred and eighty degrees from end to end and reflecting means for each light beam, the planes of the reflecting means, of the tape portions at the light apertures and of the screens being all vertical to a common plane whereby the images on the screens will move in a direction opposite to that of the tape portion being projected.

24. Projecting apparatus of the character described comprising a plurality of apertures, screens in different inspection areas, light converging means for directing a single converging light beam through said light apertures, means for successively drawing said tape across said light apertures in opposite directions, and means including an objective lens unit and reflecting means for intercepting each of the image impressed subordinate light beams emerging from the tape and directing them at one of said screens, the objective lens unit for each subordinate light beam rotating the image one hundred and eighty degrees end for end and diverting such subordinate light beam.

25. Projecting apparatus of the character described comprising two parallel light apertures, screens in different inspection areas, light converging means for directing converging light rays through said light apertures, means for successively drawing marked tape across said light apertures, and means including an objective lens unit and reflecting means for intercepting each of the image impressed subordinate light beams emerging from the tape and directing them at one of said screens, the objective lens unit for each subordinate light beam rotating the image one hundred and eighty degrees end for end and diverging the subordinate light beam.
